(57) **CLAIM**

I claim the ornamental design for an excavator hydraulic breaker rack, as shown and described.

DESCRIPTION

FIG. 1 illustrates an upper, forward, side perspective view of an excavator hydraulic breaker rack in accordance with the present invention;

FIG. 2 illustrates an environmental, upper, forward, side perspective view of an excavator hydraulic breaker rack in accordance with the present invention;

FIG. 3 illustrates a forward perspective view of an excavator hydraulic breaker rack in accordance with the present invention;

FIG. 4 illustrates a left side perspective view of an excavator hydraulic breaker rack in accordance with the present invention;

FIG. 5 illustrates a right side perspective view of an excavator hydraulic breaker rack in accordance with the present invention;

FIG. 6 illustrates a top perspective view of an excavator hydraulic breaker rack in accordance with the present invention; and,

FIG. 7 illustrates a rearward perspective view of an excavator hydraulic breaker rack in accordance with the present invention.

The broken lines show excavator hydraulic breakers stored on the rack that form no part of the claimed design.

1 Claim, 7 Drawing Sheets
